UNITED STATES PATENT OFFICE

ALPHONSE KNOEDLER, OF SOUTH ORANGE, NEW JERSEY

DESIGN FOR AN UMBRELLA HANDLE OR SIMILAR ARTICLE

Application filed March 27, 1930. Serial No. 35,044. Term of patent 7 years.

To all whom it may concern:

Be it known that I, ALPHONSE KNOEDLER, a citizen of the United States, residing at South Orange, county of Essex, and State of New Jersey, have invented a new, original, and ornamental Design for an Umbrella Handle or Similar Article, of which the following is a specification, reference being had to the accompanying drawing, forming part thereof.

The figure is an elevation of an umbrella handle or similar article, embodying my new design.

I claim:—

The ornamental design for an umbrella handle or similar article, as shown.

ALPHONSE KNOEDLER.
